UNITED STATES PATENT OFFICE.

CHARLES D. WATKINS, OF NEWARK, NEW JERSEY.

SHOE-POLISHER.

1,308,462.

Specification of Letters Patent.

Patented July 1, 1919.

Application filed July 6, 1918. Serial No. 243,528.

To all whom it may concern:

Be it known that I, CHARLES D. WATKINS, an insurance surveyor, citizen of the United States, residing at Newark, in the 5 county of Essex and State of New Jersey, have invented certain new and useful Improvements in Shoe-Polishers, of which the following is a specification, reference being had to the accompanying drawings.

10 This invention relates to shoe polishers, and particularly that class of shoe polishers wherein there is provided a supporting plate or strip carrying a polishing felt and a handle connected at its ends to the strip.

15 The general object of this invention is to provide a very simple and cheaply constructed shoe polisher of this character, having very few parts, and consisting of a felt supporting strip, a handle strip, and means 20 whereby they may be expanded with relation to each other or allowed to fold flat against each other, to thus provide an article which may be readily packed in small compass.

25 A further object is to provide very simple means for holding the handle and supported strip in their expanded relation.

Other objects will appear in the course of the following description.

30 My invention is illustrated in the accompanying drawing, wherein:—

Figure 1 is a longitudinal sectional view of my improved shoe polisher or cleaner;

Fig. 2 is a top plan view of the device;

35 Fig. 3 is a longitudinal section showing the device collapsed;

Fig. 4 is a transverse section on the line 4—4 of Fig. 1.

Referring to these figures, 10 designates 40 the supporting strip which may be of thin wood or metal. Preferably this supporting strip will be made of a strip of wood about one-sixteenth of an inch in thickness and which, therefore, has a considerable degree 45 of resilience. Disposed over the strip 10 is a handle strip 11 which is also preferably made of wood, the middle portion of this strip being relatively narrower than the ends so as to provide a good grip. The extremities of the strip 11 are connected to the extremities of the strip 10 in any suitable manner as for instance by the U-shaped connecting strips 12, which are held to the wooden strips 10 and 11 by means of staples 13 or 55 in any other suitable manner. I do not wish to limit myself to the use of these metal con-

necting members 12 as in some cases thin leather or other like material will be used fastened to the wooden strips by glue.

Glued or otherwise attached to the under 60 face of the strip 10 is a layer of polishing material 14 which is preferably of relatively thick felt. The ends of this layer or strip of polishing material are carried over upon the extremities of the handle strip 11 65 and glued or otherwise attached thereto.

It will be obvious now that when the strips 10 and 11 are forced apart that the strip 10 will be curved reversely to the strip 11 and that a curved polishing surface will 70 thereby be provided. For the purpose of holding the strips 10 and 11 in their reversely curved or expanded positions, I mount upon one of the strips, and preferably the strip 10, the brace plates 15, which 75 may be made of tin or other suitable material of like nature and which, if thin, are slightly corrugated so as to give them strength. These braces 15 at their ends connected to the strips 10 or 11 are angularly 80 bent as at 16, and these braces are operatively hinged to the member 10 by means of staples 17. When the polisher is intended to be packed away, the brace plates 15 are turned down to the position shown in Fig. 85 3, and the resilience of the wooden strips 10 and 11 will cause them to take a position parallel and closely adjacent each other. When it is desired to use the polisher, however, the plates 15 are turned to the position 90 shown in Fig. 1, and will engage the under face of the strip 11 so that the strip 11 will be held in spaced relation to the strip 10, thereby forming a handle. The use of the 95 polisher is obvious.

As before remarked, I do not wish to be limited to the particular character of the material forming the various parts of this device. By making the device very simple and correspondingly cheap, it may be readily used as an advertising article, the advertisement being printed or otherwise applied to the outer surface of the handle member 11. This is another reason for attaching the brace plates 15 to the strip 10 as 100 thereby the handle surface is left entirely unbroken for the application of the advertisement thereto.

While I have illustrated felt 14 as being applied to the surface of the member 10, 110 I wish it understood that I do not want to be limited to the use of a polishing material,

as a fabric or material which may be used for cleaning shoes, may be also applied to a support of the character described, and by the term "rubbing material" as hereinafter used in the claims, I wish it understood that I include not only any polishing material but a cleaning material as well.

I claim:—

1. A polisher of the character described comprising two resilient strips operatively connected to each other at their ends and normally urged by their resilience into parallel relation, a strip of rubbing material attached to the outer face of one of the strips, the opposite strip constituting a handle, and means for holding said strips expanded including members hingedly connected to one of the strips on each side of the middle of the strip to which the members are attached and shiftable from a position parallel to said strip into a position at right angles thereto and against the inner face of the opposite strip.

2. A polisher of the character described comprising two resilient strips operatively connected to each other at their ends and normally urged by their resilience into parallel relation, a strip of rubbing material attached to the outer face of one of the strips, the opposite strip constituting a handle, and means for holding said strips expanded including two members hingedly

connected to the strip carrying the polishing fabric on each side of the middle of the strip and normally lying in substantially parallel relation to the lower strip but shiftable into a position at right angles to the strips and thereby expand the strips away from each other, said members being angularly bent at their hinged ends.

3. A polisher of the character described comprising two parallel strips of somewhat resilient material, hinged to each other at their extremities, a strip of rubbing material attached to the outer face of one of the strips, the opposite strip being reduced in width at its middle portion to form a handle, and means for holding said strips expanded comprising metallic members angularly bent at their lower edges and hingedly connected to one of said strips at said angular edges and shiftable from a position parallel to the strips into a position at right angles thereto, to thereby separate the middle portions of the strips, said members being disposed one on each side of the middle of the strips.

In testimony whereof I hereunto affix my signature in the presence of two witnesses.

CHARLES D. WATKINS.
